UNITED STATES PATENT OFFICE.

WILLIAM B. BARLEY, OF ROCHESTER, NEW YORK, ASSIGNEE TO FEARLESS DISH-WASHING CO., OF ROCHESTER, NEW YORK, A CORPORATION OF NEW YORK.

DISH-HOLDER.

1,125,444.

Specification of Letters Patent.

Patented Jan. 19, 1915.

Application filed May 9, 1914. Serial No. 387,082.

To all whom it may concern:

Be it known that I, WILLIAM B. BARLEY, of Rochester, in the county of Monroe and State of New York, have invented certain new and useful Improvements in Dish-Holders; and I do hereby declare the following to be a full, clear, and exact description of the same, reference being had to the accompanying drawings, forming a part of this specification, and to the reference-numerals marked thereon.

My invention relates to dish washing machinery, and it has for its object to afford a novel construction for holding dishes and other articles while in the process of washing, and which is especially adapted for carrying cups, although its use is not limited to this class of articles.

A further purpose of the invention is to provide a structure in which cups may be nested for washing so as to accommodate a maximum number, while at the same time fully protecting them from contact with each other and from breaking or cracking from any other reason, the parts being arranged so as to form a protection for the handles.

Another object of the construction is to provide for packing the cups in a plurality of layers arranged one above the other, the uppermost layer being removable as an entirety to permit access to the articles underneath.

Still a further purpose of my improvement is to provide a construction that enables the parts which contact with the cups to be made of wood, so as to prevent chipping or discoloring which is likely to result when the cups are engaged by metallic portions.

To these and other ends the invention consists in certain improvements and combinations of parts, all as will be herein-after more fully described, the novel features being pointed out in the claims at the end of the specification.

In the drawings: Figure 1 is a view in side elevation of a metal basket such as employed in washing machinery, and showing the application of my improvements to the same; Fig. 2 is a plan view; Fig. 3 is a side elevation showing the removable tray supported on one of the side walls of the basket in vertical position; Fig. 4 is a perspective view of the removable tray; Fig. 5 is a plan

view of the basket with the tray removed, and Fig. 6 is a perspective view of a frame which is attached near the bottom of the basket for retaining the lowermost layer of cups.

Similar reference characters in the several figures indicate the same parts.

For a brief understanding of the invention generally, it may be stated that it consists in furnishing a basket, such as commonly employed in washing machinery for holding dishes, with stationary means at the bottom for supporting and spacing a lower layer of cups, and a removable tray adapted to be supported within the top of the basket for carrying an upper layer of cups, although it is within the scope of my invention to construct the removable tray in such a manner as to adapt it for silverware or other articles of similar character.

The removable tray is preferably provided with means for supporting it in vertical position on one of the side walls while permitting access to the bottom of the basket, so that it may be kept in a convenient place while the lower layer of cups is being positioned.

In the present embodiment of my invention, A designates a wire basket, such as commonly employed in washing machines, and provided with handle portions a by which it may be lifted in and out of a liquid receptacle.

Attached to the bottom of the basket are a series of cup supporting members in the form of strips b which are preferably made of wood and may be attached in any manner. The cups are adapted to have their sides rest upon the supporting members b, with the handles turned downwardly, as shown in Fig. 1, and arranged above the supporting members are a series of spacing members or strips disposed at right angles to the supporting members, as designated at c. The spacing members c are preferably part of a frame including end pieces c', which is secured to the walls of the basket in any convenient manner. The spacing members c are provided with enlargements or projections c² for spacing the cups of each series, the cups being arranged alternately in opposite directions. Thus, the recess c³, formed by the projections c², receives the bottom of a cup, whereas the same spacing member or strip receives the

tops of the cups which are disposed on opposite sides of the intermediate cup, as appears in Fig. 2. It will be readily seen that this arrangement permits me to utilize the 5 space within the basket to a maximum extent and at the same time hold the cups firmly and prevent their shifting out of position.

In conjunction with the means for supporting and spacing cups at the bottom of the basket, I also employ a removable tray, so as to utilize the upper portion of the basket which lies above the lower layer of cups, and this tray may be in the form of 15 a tray for silverware or other articles or it may be in the nature of a removable cup supporting and spacing tray, in which latter event it is constructed so as to operate in a manner similar to the parts already described 20 which are located at the bottom of the basket.

With this end in view, I utilize a frame comprising spacing members or bars d which are held together by means of end 25 portions d' , and serve to arrange the cups in series, there being facilities for supporting three cups in each series in the embodiment which I have described. The spacing members d are provided with downward extensions d^2 , to the bottoms of which are attached the supporting members or strips d^3 which afford and constitute supporting flanges upon which rest the sides of the cups as shown in Figs. 1 and 2. The spacing 30 members d also carry projections or abutments d^4 which space the cups of each series, and afford recesses for the tops and bottoms 35 of the cups as clearly shown in Fig. 2, the arrangement of the cups in each series being the same in the removable tray as in the construction which I have already described 40 at the bottom of the basket.

It is desirable to have the removable tray readily accessible while the bottom of the 45 basket is being filled, and it is preferable to employ means for supporting the tray upon one of the walls of the basket. To this end, the supporting members or strips d^3 are extended far enough beyond the extensions d^2 50 to afford recesses d^5 by which the upper edge of a side wall may be engaged as shown in Fig. 3, the ends of the spacing strips of the tray resting against the outer face of the wall. When the bottom of the basket has 55 been entirely filled, the tray can be quickly positioned and also filled, the parts being then ready to be submerged in the washing liquid. The tray is held resting upon

the upper edge of the basket by means of bars d' , the ends of which extend beyond the 60 frame of the tray and are adapted to rest upon the upper edges of the walls.

d' designates a bracing member for holding the parts of the frame of the tray more rigidly, when it is made of separate elements 65 that are attached, as in the case of a wooden construction, such as I have shown, although it will be understood that I may cast the frame from aluminum or any other substance which can be successfully used in this 70 relation, and I consider such a modification or departure as coming within the scope of my improvements.

I claim as my invention:

1. The combination with a basket, of a 75 removable cup holding tray embodying a series of division members separating the cups, and supporting flanges at the base of said division members engaging the sides of the cups, said division members having 80 recesses to receive the tops and bottoms of the cups.

2. The combination with a basket, of a removable cup holding tray embodying a frame consisting of a series of division strips 85 for separating the cups into transversely arranged series, projecting portions of said strips acting to space the cups of each series and holding them out of contact with each other, and supporting flanges disposed 90 below the division strips and engaging the sides of the cups.

3. The combination with a basket, of a removable cup holding tray embodying a frame consisting of an upper portion, and 95 a lateral extension arranged below the upper portion and in spaced relation thereto affording a recess for engagement with one wall of the basket to hold the tray in a vertical position. 100

4. The combination with a basket, of a removable cup holding tray embodying a frame consisting of a series of division strips for separating the cups into transversely arranged series, the strips being recessed to 105 space the cups of each series, and supporting flanges carried by the strips and engaging the sides of the cups, the ends of said flanges being spaced from the ends of the division strips and affording recesses to engage one side of the basket and hold the tray 110 in vertical position.

WILLIAM B. BARLEY.
